UNITED STATES PATENT OFFICE.

PHILIPP SEILER, OF CHICAGO, ILLINOIS, ASSIGNOR, BY MESNE ASSIGNMENTS, TO ROSE CONNETT, OF UPPER MONTCLAIR, NEW JERSEY.

ACOUSTICAL INSTRUMENT.

No. 879,917.

Specification of Letters Patent.

Patented Feb. 25, 1903.

Application filed July 5, 1904. Serial No. 215,390.

To all whom it may concern:

Be it known that I, PHILIPP SEILER, a citizen of the United States, residing at Chicago, in the county of Cook and State of Illinois, have invented a new and useful Improvement in Acoustical Instruments, of which the following is a specification.

This invention relates to certain improvements in acoustical instruments, as for instance toy horns and has for its object to provide a device of this character of a simple and inexpensive nature and of an improved construction which shall present certain features of novelty whereby sounds of different natures are adapted to be produced, so that the use of the device is calculated to afford greater amusement to children and other persons.

The invention consists broadly in an acoustical instrument in the form of a conical, elongated hollow body, one end of which is resonant and provided with a clapper and the other end is provided with a reed.

It also consists in certain novel features of the construction, combination and arrangement of the several parts of the instrument, whereby certain important advantages are attained and the device is rendered simpler, cheaper and otherwise better adapted and more convenient for use, all as will be herein-after fully set forth.

The novel features of the invention will be carefully defined in the claims.

In the accompanying drawings which serve to illustrate the invention—Figure 1 is a perspective view showing a toy horn embodying my improvements, and—Fig. 2 is an axial section taken through the device and showing certain features of construction.

In the drawings I have shown my invention in the form of a toy horn in which 1 indicates the body portion of the horn which is formed from sheet metal in a well known conical form having at its larger end an opening 2 and having at its smaller end 2^a a diagonal or beveled reed opening over which is extended a reed 3.

4 indicates a metal tube slipped over the smaller end of the tapered body portion 1 at which the reed is arranged, and 5 indicates a mouth piece of wood or the like slipped upon the end of the tube 4, said tube and mouth piece being of a length adapted to form a convenient handle for the device, so that the hand of the user is not required to be applied

over the end of the body portion 1 so as to lessen in any way the vibrations of the device in sounding.

The conical body portion of the horn is adapted to serve as a bell and in it is arranged a clapper or striker 6 held on a wire or reed 7, the end of which has an eye 8 for loose connection with the downwardly bent end 9 of a support 10 which is preferably formed of a wire the upper part of which is bent laterally and passed through the wall of the body portion 1 near the smaller end thereof and has its outer extremity bent over the outside of the body portion and secured thereto by means of solder or the like. The clapper or striker 6 is adjacent to the larger end of the tapered horn and is adapted, when the device is swung to and fro, to strike upon the wall of the horn adjacent to its larger end.

In the use of the instrument, it may be used either as an ordinary horn, the mouth piece being applied to the lips so that the horn may be blown or sounded in the usual way, or it may be used as a bell, the tube 4 and mouth piece 5 being grasped in the hand so that the device may be swung to cause the loosely mounted clapper or striker to swing back and forth so as to strike the walls of the body portion so that a sound somewhat similar to that of a cow-bell is produced, or the outer end may be swung back and forth while it is being blown, thus producing a mingling of the two sounds.

An instrument constructed as above described is of an extremely simple and inexpensive nature and is especially well adapted for use since it permits of being employed to produce either the sound of an ordinary toy horn or of a bell, or both, so that the device is especially well adapted for use in celebrations of various kinds, as for example, political gatherings and the like.

It will also be obvious from the above description that the instrument is capable of some modification without material departure from the principles and spirit of the invention, and for this reason I do not wish to be understood as limiting myself to the precise form and arrangement of the several parts of the device herein shown in carrying out my invention in practice.

Having thus described my invention, I claim—

1. An acoustical instrument comprising a conical, elongated, hollow body, the larger

end of which is resonant and provided with a clapper and the smaller end is provided with a reed.

2. An acoustical instrument comprising a conical, elongated, hollow body, the larger end of which is resonant and the smaller end is provided with a reed, a support intermediate the ends of the body, and a clapper loosely connected with the support in position to strike the inner walls of the resonant end.

3. A horn, having a body, a striker tongue suspended within the body of the horn and adapted to strike the same, whereby the body and said tongue form a bell.

4. A horn provided with a flaring body portion, and a striking tongue suspended within the flared body and adapted to strike the same, whereby the body and said tongue comprise a bell.

5. A horn having a body, a rod suspended within the body of the horn, and provided with a striker adapted to strike the inside of the horn body.

25 6. A horn having a resonant body, and a striker having means for supporting it in relation to said body and adapted to strike the

same, whereby the resonant body and said striker form a bell.

7. A horn having a mouthpiece portion and a flaring extension therefrom, a flexible rod or wire secured to the inside of the horn intermediate the mouthpiece and end of said flaring extension, and a striker on the end of said flexible rod or wire adapted to strike the inside of said extension.

8. A horn having a mouthpiece portion and a flaring extension therefrom, a striker adapted to swing within said extension and strike the inside thereof, and means for flexibly supporting said striker within the horn and from a point between said mouthpiece and the end of said extension.

9. A horn having a resonant body, and a striker inclosed therein, whereby the resonant body and said striker form a bell.

In testimony whereof I hereunto have signed my name in presence of two subscribing witnesses at Chicago, Illinois, this 20th day of June, 1904.

PHILIPP SEILER.
